FIG. 3

FIG. 4

Fig. 1 is a diagrammatic view of a bedspread showing my new design;

Fig. 2 is an enlarged view of the area A—B—C—D shown in Fig. 1;

Fig. 3 is an enlarged view of the area B—E—F—C shown in Fig. 1; and

Fig. 4 is an enlarged view of the area E—G—H—F shown in Fig. 1.

The area J—K—L—M—H—F—C—D on the opposite side of the center line D—C—F—H is equal and opposite to the area A—B—E—G—H—F—C—D.

The design disclosed is composed of chenille tufts upon a plain background, as particularly shown in Figs. 2, 3 and 4.

I claim:

The ornamental design for a bedspread or similar article, substantially as shown and described.
